UNITED STATES PATENT OFFICE.

HERBERT C. LEONARD, OF ACUSHNET, MASSACHUSETTS, ASSIGNOR TO ATLAS TACK COMPANY, OF FAIRHAVEN, MASSACHUSETTS, A CORPORATION OF NEW JERSEY.

STRIP-FEEDING MECHANISM.

1,109,237.

Specification of Letters Patent. Patented Sept. 1, 1914.

Application filed May 6, 1913. Serial No. 765,783.

To all whom it may concern:

Be it known that I, HERBERT C. LEONARD, a citizen of the United States, and resident of Acushnet, in the county of Bristol and 5 State of Massachusetts, have invented certain new and useful Improvements in Strip-Feeding Mechanism, of which the following is a specification.

This invention relates to automatic mechanism for feeding blank strips.

The operation of the strip-feeding mechanism of the present invention is, in general, similar to that of the mechanism shown in my copending application Serial No. 687,757, 15 filed April 1, 1912. The present invention embodies various improvements whereby the efficiency and accuracy of the mechanism are improved.

Of the accompanying drawings, which 20 illustrate my invention: Figure 1 represents a side elevation of strip-feeding mechanism in co-operative relation to a tack-making machine of well-known construction and operation. The strip-feeding mechanism is inclined as shown by this figure. Fig. 2 represents a side elevation, on a larger scale, of the delivery end of the strip-feeding mechanism and the adjacent parts of the tack-making machine. In this figure and in other 25 figures the position of the strip-feeding mechanism is represented as being horizontal, solely for the purpose of expediting the drawings. Fig. 3 represents a top plan view of the delivery end of the strip-feeding mechanism, omitting the barrel through 30 which the strip is fed. Fig. 4 represents a top plan view, on a larger scale, of a clutch-operating device included in Fig. 3. Fig. 5 represents an elevation, on a larger scale, of 35 a barrel-stopping device included in Fig. 2. Fig. 6 represents a side elevation of the other end of the strip-feeding mechanism. This figure, if placed at the right of Fig. 2, 40 may be read as a continuation of Fig. 2. Fig. 7 represents a top plan view of the mechanism shown by Fig. 6, and bears the same relation to Fig. 3 as that borne by Fig. 6 to Fig. 2. Fig. 8 represents a top plan view of a portion of the mechanism by 45 which the strips are transferred laterally from a magazine into the feed barrel. The same mechanism is included in Fig. 7, but the mechanism is shown in different positions by the two figures. Fig. 9 represents 50 a side elevation of the feed barrel, portions

of which are broken away. Fig. 10 represents a cross section in the plane indicated by line 10—10 of Fig. 9. Fig. 11 represents an elevation of strip-engaging means which moves through the barrel to feed the strip. 60 Fig. 12 represents an elevation of the same strip-engaging means from a viewpoint at right angles to that of Fig. 11. Fig. 13 represents a cross section in the plane indicated by line 13—13 of Fig. 11. Fig. 14 represents a longitudinal vertical section through that portion of the feed barrel which is shown at the right of Fig. 9. Fig. 15 represents an elevation of a magazine for blank strips, and means for transferring the strips 65 to the feed barrel. Fig. 16 represents a vertical section, on a larger scale, in the plane indicated by line 16—16 of Fig. 15. Fig. 17 represents a vertical section, on a larger scale, in the plane indicated by line 17—17 of Fig. 15, some of the parts being shown in 70 a different position. Fig. 18 represents a horizontal section of the gearing by which the strip-feeding mechanism is operated. Fig. 19 represents a vertical cross section 75 through the feed mechanism, in the plane indicated by line 19—19 of Fig. 1. Fig. 20 represents an elevation of a clutch-operating device included in Fig. 19. Fig. 21 represents an elevation of a barrel-starting device included in Fig. 19. Fig. 22 represents a vertical section in the plane indicated by line 22—22 of Fig. 7.

The same reference characters indicate the same parts wherever they occur. 90

Although the drawings show the present invention as applied to a tack machine, it is to be understood that it is not limited to this one use and that the claims hereinafter set forth are intended to cover the various 95 features of the invention regardless of the specific machine to which the strip-feeding mechanism is applied.

Before describing the details of my present invention I will briefly outline the operation. The strips are fed through a barrel to the means which operates upon the strips. The barrel is oscillated so as to present a strip first in one position and then in another. The strips are inserted one by one 100 into the barrel through a slot in the side of the barrel. A magazine for a plurality of blank strips is disposed at one side of the barrel, and suitable mechanism is provided for transferring the strips from the maga- 105 110 115

zine into the barrel. The feeding movement of the strip through the barrel is caused by strip-engaging means which moves longitudinally through the barrel. When each strip 5 has been used as far as possible, leaving a short remnant, the feeding device by which the strip is engaged moves in the reverse direction, carrying the remnant away from the machine which operates upon the strip.

10 The feeding device is caused to discharge the remnant after having carried the remnant a sufficient distance from the delivery end of the barrel toward the opposite end thereof. While the feeding device is retracted beyond the point where a new blank strip is inserted into the barrel, the strip-transferring mechanism is operated to transfer a new blank strip from the magazine into the barrel. The feeding device is then 15 advanced toward the new blank strip and operatively engages the same, and then feeds the new strip toward the means which operates upon the strip. This cycle of operations is repeated indefinitely so long as the 20 magazine contains blank strips. An additional supply of blank strips may be placed in the magazine from time to time as occasion requires, without interrupting the operation of the mechanism.

25 The operating mechanism includes weighted means for feeding the strip to the means which operates upon the strip, and also includes power-driven means for moving the feeding device in the reverse direction and power-driven means for moving the feeding device from its fully retracted position to strip-engaging position. The power-operated mechanism includes clutch mechanism and controlling mechanism 30 therefor, the controlling mechanism being actuated by the feeding device as follows:— While the weighted feeding means is operating to feed the strip to the means which operates upon the strip, the clutch mechanism 35 is entirely disconnected and is in what is hereinafter called a neutral position. When the strip has been fed to the limit of its feeding movement by the aforesaid weighted means, the clutch controlling mechanism is 40 thrown automatically into the "reverse" position by a power-driven actuator. The power-driven mechanism then moves the strip-engaging device in the opposite direction to retract the same, and when the device 45 is fully retracted the clutch mechanism is shifted automatically from "reverse" position to "forward driving" position to carry the strip-engaging device to strip-engaging position. When the strip-engaging device 50 reaches strip-engaging position, the clutch mechanism is placed automatically again in "neutral" position, and the strip-engaging device is then moved as before by the weighted means to feed the fresh blank strip through 55 the barrel. The operation just described is

substantially the same as that in my aforesaid copending application, but the mechanism for performing the several functions embodies various improvements which are hereinafter described in detail and are shown 70 upon the accompanying drawings and hereinafter claimed.

Proceeding now to a description of the mechanism,—Figs. 1 and 2 show portions of a machine 25 for operating upon a blank strip, this machine in the present instance being one for making tacks. It is immaterial in just what manner and to what end this machine operates, and it is therefore unnecessary to describe any of its 75 details. A blank strip is fed to the machine 25 through a barrel 26. This barrel is oscillated for the purpose of placing the blank strip first in one position and then in another position with reference to the machine 25. The barrel is mounted in bearings 27 and 28 in such manner that it may be readily detached. The bearing 27 has two studs, such as that indicated at 29 in Fig. 2, which occupy holes 30, 30 (see Fig. 3) in 80 a stationary support 31. One or more springs, such as that indicated at 32 in Fig. 2, hold the bearing seated upon its support. These springs may be readily detached to permit detachment of the bearing from its 85 support. The bearing 28, which is shown by Figs. 1, 6 and 7, receives a circular collar 33 which is affixed to the barrel. This collar turns in the bearing and prevents longitudinal movement of the barrel but permits lifting the barrel away from the bearing. When the collar is lifted out of the bearing 28 and when the bearing 27 is lifted from the support 31, the barrel may be removed. 90

The main frame of the feeding mechanism 95 is indicated at 34. The end which is toward the machine 25 rests upon and is supported by a bracket 35 affixed to the machine, and the opposite end of the frame is supported by a standard 36. As shown by Fig. 1, the 100 frame 34 is inclined, its lower end being toward the machine 25. The inclined arrangement of the frame is not shown in the other figures, but it is to be understood that the only reason for not showing the inclined 105 arrangement in the other figures is to facilitate the making of the drawings.

The barrel is oscillated in its bearings through suitable connections which receive their motion from the machine 25. For this 110 purpose a rockshaft 37 (see Fig. 1) is mounted in suitable bearings on the machine 25. An operating arm 38 affixed to the rockshaft is oscillated by any suitable means (not shown), the position of the arm as 115 shown by Fig. 1 being about half way between its limits of movement. An arm 39 affixed to the rockshaft is suitably connected to a rod 40 which is reciprocated longitudinally. This rod is provided with a suitable 120

connecting device, indicated as a whole at 41, whereby the rod is disconnectibly connected to a stud 42 carried by a bell-crank lever 43. The connection 41, when in operative position, rests upon the stud 42 and is lifted from time to time, as hereinafter explained, to break the connection between the rod and the bell-crank lever. This lever is affixed to a rockshaft 44 which is mounted in suitable bearings in the frame 34. One arm of the bell-crank is connected by a suitable connection 45 with a flexible strap 46 which is anchored to the barrel 26. At the opposite side of the frame 34 an arm 47 (Figs. 6 and 7) is affixed to the rockshaft. This arm is connected by another connecting device 45 with a second flexible strap 48 which is anchored to the barrel. The straps 46 and 48 extend part way around the barrel in opposite directions, and the arrangement of the several parts is such that the barrel is oscillated positively in both directions when the bell-crank 43 is oscillated. A spring 49 acting upon the bell-crank 43 is provided to move the barrel always to the same position when the connection 41 is lifted, for the purpose of holding the barrel in strip-receiving position. This position, as shown by Figs. 16 and 17, is determined by a stop 50 which co-operates with the arm 47.

The barrel has a longitudinal slot 51 in its side for enabling a blank strip to move laterally into the barrel. Recesses 52 are formed in the barrel for the reception of pushers, hereinafter described, which transfer a blank strip from the magazine into the barrel. The barrel also has recesses 53 for the reception of suitable devices, herein-after described, which co-operate with two of the pushers to hold the blank strip in operative position upon the pushers. The barrel has still other recesses, indicated at 54, for the reception of suitable devices, herein-after described, which move into the barrel with the blank strip to prevent the end of the strip from sagging and for holding the end of the strip in line with the strip-engaging devices by which the strip is fed to the machine 25.

The strip is fed through the barrel to the machine 25 by mechanism which includes the device shown by Figs. 11, 12 and 13. This device includes grippers 55 which engage the rear end of the strip. One of the grippers has a shoulder 56 which abuts against the rear end of the strip. The grippers are pivotally connected with each other by a pin 57, and they have extensions 58 which are normally spread apart by springs 59 to close the grippers on the blank strip. Links 60 are pivotally connected to the extensions 58 respectively and are connected to a rod 61 by a pivot pin 62. The rod 61 is provided with shoes 63 which have sliding

engagement with the interior surface of the barrel. The rear end of the rod 61 has a fin 64 which projects through the slot 51 to engage a U-shaped yoke 65 affixed to a sliding carriage 66. The U-shape of this yoke 65 is shown by Fig. 19, but in this figure the extremities of the U-portion are broken away. The rod 61 receives its movement through the barrel from the carriage 66 and the latter is reciprocated as hereinafter explained. The fin 64 is formed with a notch 67 which is occupied by the yoke. The engagement of the fin 64 with the edges which define the longitudinal slot 51 in the barrel causes the rod 61 to oscillate with the barrel, and the fin is thereby oscillated relatively to the yoke 65, but the shape of the yoke preserves the desired co-operative engagement. In order to prevent relative rotative movement of the rod 61 and barrel while the fin 64 is opposite any one of the recesses of the barrel, the rod is provided with pins 68.

Cam members 69 are secured upon the interior of the barrel for the purpose of opening the grippers 55 when the latter are retracted. These cam surfaces are engaged by the links 60, with the result that the extensions 58 are moved toward each other, thus opening the grippers. The sliding shoes 63 are cut away (see Fig. 13) to provide recesses 70 to enable the shoes to pass the cams 69 without engaging the same.

The sliding carriage 66 slides upon guiding flanges 71 formed upon the interior of the frame 34, as shown by Figs. 16 and 19. The carriage is overlapped by strips 72 which keep it seated upon the flanges. A sprocket chain 73 is secured to the carriage and runs upon sprocket wheels 74 and 75, the first of which is loosely mounted upon a shaft 76 near the delivery end of the feeding mechanism, and the other of which is mounted near the opposite end of the feeding mechanism. A cord or chain 77 provided with a weight 78 is connected at 79 to the chain 73. The other end of the cord or chain 77 is secured at 80 to a fixture, the same in this instance being a part of the frame 34. The cord or chain 77 passes over an idle roll 81, and the tendency of the weight 78 is to draw the lower stretch of the chain 73 away from the machine 25 and thereby move the sliding carriage toward the machine 25. The function of this mechanism is to impart feeding movement to the strip which is in the barrel to carry the strip forward toward the machine 25. The sprocket wheel 74 is associated with suitable driving mechanism by which the sliding carriage is retracted and by which it is carried forward from its fully retracted position to strip-engaging position, as herein-after explained.

The magazine which contains the blank

strips is shown by Figs. 1, 7, 15, 16 and 17. It comprises uprights 82 of which there are two pairs, one pair of said uprights being mounted upon one end of a magazine frame 83 and the other pair being mounted at the opposite end of said frame. This frame, as shown by Fig. 16, is secured to the frame 34. The uprights 82 engage the ends of blank strips such as that indicated at α , the blank strips being piled one upon another between the uprights, as shown by Figs. 15 and 16. The pile of blank strips is shown somewhat conventionally in Fig. 15, the ends of the pile being indicated by vertical dotted lines α' , and the top of the pile being indicated by a horizontal broken line α^2 . The bottom strip in the magazine rests upon stationary blocks 84 whose upper surfaces are in a plane which intersects or nearly intersects the axis of the feed barrel 26. The bottom strip in the magazine is moved laterally into the feed barrel through the longitudinal slot 51 of the latter. For this purpose the magazine is provided with slides 85 each of which has a push finger 86. These slides are movable transversely with relation to the axis of the feed barrel. Each push finger has a shoulder 87 and an extension 88. When the slides are fully retracted from the feed barrel, the extensions 88 underlie and engage the bottom strip α , in the magazine. When the slides are moved toward the feed barrel the shoulders 87 engage the side edge of the bottom strip and push the strip from under the remaining strips, the push fingers advancing into the feed barrel through the recesses 52. During this movement the bottom strip is supported by the extensions 88. No more than one strip at a time can be removed from the magazine, because the magazine is provided with abutments 89 which engage the second strip on the side toward the feed barrel. The strip is positioned centrally in the barrel by adjustable stop-screws 90 carried by the barrel.

The slides 85 are operated by bell-crank levers 91 which are pivotally connected to the frame 83 by fulcrum studs 92, as shown by Figs. 7 and 16. Each slide 85 has on its under side a swiveled block 93. These blocks are engaged by the bell-crank levers. The levers are connected with each other by a tie-rod 94 by which they are caused to move in unison. A rod 95 extends from one of the bell-crank levers to a three-armed operating lever 96. (See Figs. 7 and 8). The fulcrum of the lever 96 is indicated at 97. One of the arms of the lever 96 carries a roll 98, and another of the arms carries a roll 99. These rolls are arranged to be engaged and moved by a plate 100 which is mounted upon the sliding carriage 66. A top plan view of this plate is shown by Figs. 3 and 8. 65 The plate has an inclined cam surface 101

for engaging the roll 98 to transfer a blank strip from the magazine to the barrel, and the plate has an inclined cam surface 102 which engages the roll 99 to retract the slides 85 from the barrel. A spring 103 connecting one arm of the lever 96 with the rod 95 holds the transferring mechanism in retracted position and prevents the pushers from being advanced by vibration or other undesirable cause. 75

I have provided means for holding the blank strip in the desired position upon the push fingers during the transferring operation. The means for this purpose comprise swinging fingers 104. (See Figs. 15 and 16). In Fig. 15 the pushers and fingers 104 are retracted, while in Fig. 17 they extend into the feed barrel. The fingers 104 are affixed to rockshafts 105. These rockshafts have bearings in blocks 106 which are mounted, preferably adjustably, upon a bar 107. Levers 108 are affixed to the upper ends of the rockshafts. The free ends of the levers are connected by a rod 109. Helical springs 110 surround the rockshafts and are compressed between the bearing blocks 106 and the fingers 104. The springs keep the levers 108 seated upon the bearing blocks 106 as in Fig. 16, but when the transferring mechanism is in operation the springs act to keep the fingers 104 upon the blank strip. The fingers are beveled as shown at α' , in Fig. 16 to enable a blank strip to pass under them. When the pushers are retracted from the feed barrel the free ends of the fingers 104 occupy the position shown by Figs 7 and 15. The rockshafts 105 are oscillated when the pushers move forward to transfer a blank strip to the feed barrel, the free ends of the fingers 104 being thereby advanced with the blank strip so as to overlap the same and to keep the blank strip in the desired position upon the push fingers. The fingers 104 enter the feed barrel through the recesses 53. (See Fig. 9). The feed barrel as shown by Fig. 9 is turned 180 degrees from strip-receiving position; but if the sheet bearing this figure be inverted, the feed barrel will look as it does when it is in strip-receiving position and when viewed from the magazine. The fingers 104 are actuated by the transferring mechanism through the medium of a lever 111 and connecting rod 112. The fulcrum of the lever is indicated at 113. One arm of the lever has a pin-and-slot connection 114 with the rod 95. (See Figs. 7 and 8.) The free ends of the fingers 104 are thus caused to advance in unison with the push fingers which transfer the blank strip. In Fig. 8 the axis 120 of the feed barrel is indicated by broken line 26x.

In order to support the rear end of the blank strip in line with the grippers 55, I have provided a swinging finger 115 and I 130

have provided a finger 116 which coöperates with the finger 115 for the purpose of keeping the strip seated upon the latter. These fingers enter the feed barrel through the recesses 54 shown in Fig. 9. This finger 116 is, to all intents and purposes, like the fingers 104 which coöperate with the push fingers 86 but the fingers 115 and 116 are deflected by the grippers and caused to move out of the feed barrel before the fingers 86 and 104 are retracted. The finger 115 is affixed to a rockshaft 117 at whose lower end is a lever 118. This lever is connected by a rod 119 with the lever 111, as shown by Figs. 7, 8 and 22. Referring to Fig. 22, the lever 111 has a pin 120 which occupies a slot 121 in the rod 119. A spring 122 is stretched between the pin 120 and a pin 123 carried by the rod 119. The pin-and-slot connection permits longitudinal movement of the rod relatively to the pin 120, and the spring 122 normally holds the rod in the position shown best by Figs 7 and 8. Such relative longitudinal movement of the rod occurs when the finger 115 is deflected by the grippers as hereinafter explained.

The finger 116 is mounted in the same manner as the fingers 104, and no further explanation is required except as follows. The upper end of the rockshaft which carries the fingers 116 is provided with a lever 124. A spring 125 normally holds the free end of this lever against a pin 126 carried by the rod 112. One end of the spring is connected to the rod, and the other end is connected to the lever. This yielding connection causes the fingers 116 to swing in unison with the finger 115 into the feed barrel when a blank strip is being transferred into the barrel, and permits the finger 116 to be deflected by the grippers. The fingers 115 and 116 are shown in strip-supporting position by dotted lines in Fig. 16, and are shown in the same position by Fig. 8.

Assuming that the transferring mechanism has been operated to transfer a blank strip into the feed barrel, the grippers advance to grip the strip, being held open for that purpose until released by the cams 69. The grippers, after engaging the strip, advance and engage the fingers 115 and 116 and force these fingers out of the feed barrel. The direction of movement of the grippers at this time is from right to left with reference to Fig. 15. After the grippers have thus deflected the fingers 115 and 116, but before the grippers reach the nearest push finger 86 and swinging finger 104, the latter and their duplicates are retracted from the feed barrel by a movement of the three-armed lever 96.

The adjusting screws 90 carried by the barrel for locating the strip therein are diametrically opposite the slot 51. There is an additional strip-engaging screw 90 which,

as shown by Fig. 9, is in line with the slot 51 and on the same side of the barrel. The latter screw is between the forward end of the slot and the delivery end of the barrel. One side edge of the blank strip slides upon the inner end of this screw, and the strip is brought into such sliding engagement before the transferring mechanism is retracted from the barrel. The blank strip is then guided at the front end by the foremost screw 90, and at the rear end by the grippers, and at intermediate points by the screws 90 which are diametrically opposite the slot 51. So long as the push fingers remain in the barrel as shown by Fig. 17, the shoulders 87 act as guides for guiding the longitudinal movement of the strip. Before the transferring mechanism is retracted from the barrel, the forward end of the strip enters between converging guiding surfaces 127 formed on filling pieces 128 which are affixed in the delivery end of the barrel. (See Figs. 9 and 10). These filling pieces are grooved, as indicated at 129, for the side edges of the strip, and the grooves are of such depth as to accommodate a blank strip of a width almost equal to the inside diameter of the barrel. When a strip of less than maximum width is used, the adjustable screws 90 are used to keep the same central with relation to the barrel. A sufficient space is left between the filling pieces 128 to enable the grippers to pass out through the delivery end of the barrel. Referring to Fig. 13, it will be observed that the space between the sliding shoes 63 is sufficient to enable the shoes to pass the adjusting screws 90 without engaging the same.

When the forward end of the blank strip passes out from the delivery end of the barrel, it engages a pair of coöoperative spring fingers 130 which are secured to the barrel. These spring fingers 130 guide the forward end of the strip so that it will enter a suitable passageway 131 which extends 105 through a nosepiece 132. This nosepiece is affixed to the barrel and engages a surface 133 of the machine 25 when the barrel is oscillated, to prevent injury to the blank strip.

The power driven mechanism for driving the sliding carriage 66 is shown by Figs. 1, 2, 3 and 18. This mechanism receives its power from the machine 25 through a belt 135. The belt passes over any suitable continuously driven pulley (not shown) of the machine 25 and over a pulley 136. The latter is affixed to a shaft 137. A sprocket wheel 138 affixed to this shaft drives a chain 139 which runs over a sprocket wheel 140 120 loosely mounted upon the shaft 76. (See Fig. 18). The shaft 137 is also provided with a gear 141 which engages a gear 142. The latter is compounded with a sprocket wheel 143 by a shaft 144. The sprocket 125 130

wheel 143 drives a chain 145 which runs over a sprocket wheel 146 loosely mounted upon the shaft 76. The sprocket wheels 140 and 146 are thus rotated continuously in opposite directions. The shaft 76 is movable longitudinally for the purpose of connecting and disconnecting suitable clutch mechanism contained in the sprocket wheels thereon. As the construction of this clutch mechanism is unimportant, and the same is fully shown in my copending application, it is unnecessary to illustrate and describe the same in detail in the present instance. It will be sufficient to state that when the shaft 76 is moved longitudinally as far as it will go toward the right, with reference to Fig. 18, the sprocket wheels 74 and 146 are operatively connected so that the sprocket 74 will be driven to move the sliding carriage 66 forwardly or toward the machine 25; and when the shaft 76 is moved longitudinally as far as it will go toward the left, the sprocket wheel 74 is disconnected from the sprocket wheel 146 and operatively connected to the sprocket wheel 140 to retract the sliding carriage 66 from the machine 25. The first of these driving connections may be called the "forward" drive, and the second may be called the "reverse" drive. When the shaft 76 is in a position midway between its forward and reverse positions, the sprocket wheel 74 is not connected to either of the sprocket wheels 140, 146, but is free to be driven independently thereof. The last-described position of the shaft 76 may be called the "neutral" position.

The strip-feeding mechanism is provided with automatic devices actuated by the sliding carriage 66 for shifting the shaft 76 to its several positions as occasion requires. For this purpose the shaft is provided with a grooved collar 147. This collar is engaged by a shipper 148. The shipper is mounted upon a fulcrum 149 and is pivotally connected to an operating rod or controller 150. The shipper is in the form of a bell-crank in plan view, as shown by Figs. 3 and 4. The pivot 151 which connects the shipper and the controller serves also as the fulcrum for an oscillatory member 152. This member is adapted to transmit motion to the shipper from a continuously vibrating actuator 153. The latter is a lever whose fulcrum is indicated at 154 in Fig. 2. The lower end of the actuator is arranged to be engaged by a collar 155 on the rod 40. The actuator is held against the collar by a spring 156. The member 152 is normally held out of the path of the actuator 153 by a spring 157, as shown by Figs. 3 and 4, a stop 158 being provided to be engaged by the member 152 when the latter is retracted. The member 152 has an arm 159 at the free end of which

stands in the path of the plate 100 which is carried by the sliding carriage 66. When the plate 100 reaches the limit of feeding movement it moves the member 152 into the path of the actuator 153, as shown by dotted lines in Fig. 4. The actuator thereupon abuts against the member 152 and moves the shipper 148 to shift the clutch mechanism from "neutral" position to "reverse" position. The sprocket wheel 74 is thereupon driven to retract the sliding carriage from the machine 25. While the sliding carriage is moving away from the machine 25, a stud 161 carried by the plate 100 engages a latch 162 which is mounted upon a lever 163. The function of this lever is to lift the connection 41 out of engagement with the stud 42 to stop the oscillatory movement of the feed barrel. The fulcrum of the lever 163 is indicated at 164. One end of a rod 165 is pivotally connected to the lever 163, and the other end is pivotally connected to a bell-crank lever 166. The fulcrum of lever 166 is indicated at 167. A lifting bar 168 is pivotally connected to the bell-crank and is provided with a grooved roll 169 which extends under the rod 40, as shown by Fig. 19. The lifting device is initially held in its lower position by a spring 170 connected to the lever 166, the inoperative position of these parts being determined by a stop-pin 171 which is arranged to be engaged by the lever 163. When the rod 40 is lifted to inoperative position it is held in that position by a detent 172. The detent is affixed to a rockshaft 173 and is disposed to engage the pin 174 which connects the bell-crank 166 and the lifting device 168. (See Fig. 19). When the lifting device moves upwardly, the pin 174 strikes the detent 172, deflecting the latter against the tension of the spring 175. The detent is thereafter hooked under the pin 174 by the action of the spring 175 and supports the rod 40 in inoperative position until the detent is retracted as hereinafter explained.

Referring again to the latch 162 (Figs. 2 and 5), this latch is mounted on the lever 163 by a pivot 176. The latch and lever have abutting portions, indicated by dotted lines in Fig. 5, whereby they are, to all intents and purposes, rigid with relation to each other when the stud 161 acts as aforesaid. The abutting portions of these members are held against each other by a spring 177 which permits the latch to swing toward the left and downwardly when the stud 161 moves toward the machine 25. The stud 161 can therefore move the lever 163 only in one direction.

The controller 150 carries an abutment 178 (Figs. 6 and 7) which is adapted to be engaged by the stud 161 when the sliding carriage is fully retracted. This coöperation of the stud with the abutment shifts the con-

troller from "reverse" to "forward" position. The controller is thereafter shifted to "neutral" position by a lever 179. The fulcrum of this lever is indicated at 180 in Fig. 7. The lever has an arm 181 at the free end of which is a roll 182. The roll is disposed in the plane of the plate 100, and is moved into the path of the plate when the controller is shifted from "reverse" to "forward" position. The forward movement of the plate then deflects the roll sufficiently to shift the controller from "forward" to "neutral" position. This last shift occurs after the grippers have taken hold of the 15 fresh blank strip but before the forward end of the strip has reached the devices of the machine 25 which act upon the strip. As soon as the clutch mechanism is thrown to "neutral" position, the weight 78 becomes 20 effective for feeding the strip toward the machine 25.

Referring again to the lifting device 168 which disconnects the oscillating means for the feed barrel,—it will be recalled that the 25 last statement concerning the detent 172 is that it supports the rod 40 in inoperative position until the detent is retracted. When a fresh blank strip has been transferred from the magazine into the feed barrel, and 30 when the transferring mechanism has been retracted from the feed barrel, the detent 172 is retracted to permit the rod 40 to drop for the purpose of operatively connecting the mechanism by which the feed barrel is oscillated. The detent is retracted during 35 the forward movement of the sliding carriage by a stud 183 carried by the plate 100. (See Figs. 3, 8 and 19). The stud 183 engages a latch 184 which is pivotally mounted upon a lever 185 by a pivot pin 186. A 40 spring 187 normally holds the upper end of the latch 184 in the path of the stud 183, as shown by Fig. 19. This device is substantially the same as the device shown by Fig. 45 5, but it is arranged to be operated only when the sliding carriage is moving toward the machine 25, the latch 184 being adapted to be deflected by the stud 183 when the latter is moving away from the machine 25. 50 The lever 185 is affixed to the rockshaft 173 which carries the detent 172. A stop-pin 188 is disposed to be engaged by the lever 185 when the detent is in operative position, the lever being held against the stop by the 55 spring 175. The direction of forward movement of the sliding carriage 66 is indicated by an arrow in Fig. 21. When the stud 183 engages the latch 184, the detent 172 is retracted from under the pin 174, thus releasing 60 the lifting device 168 and permitting the rod 40 to drop to operative position. This also returns the lever 163 to its initial position against its stop-pin 171.

Referring to Fig. 7, a spring follower 189 65 is provided for holding the controller 150 in

any one of its three positions. The controller is shown in its "neutral" position by this figure. The follower 189 engages one edge of the controller, said edge being provided with suitable notches corresponding 70 to the "reverse", "neutral" and "forward" positions of the controller.

I have provided a safety device for preventing the operation of the strip-transferring mechanism while the feed barrel is oscillating, as might otherwise occur if the clutch mechanism should be put in "reverse" position from any cause while the sliding carriage 66 is between the lever 163 and the three-armed lever 96. The rod 40 should in 75 every instance be lifted to stop the oscillatory movement of the barrel before the three-armed lever is moved to transfer a blank strip. My device for this purpose prevents the plate 100 from engaging the 80 roll 98 while the feed barrel is oscillating. The device comprises a lever 190 whose location is shown by Fig. 6 and whose construction is shown better by Figs. 19 and 20. This lever has a pivoted latch 191 connected 85 thereto by a pivot pin 192. The latch and the lever have abutting surfaces which are normally held in contact with each other by a spring 193. The device is so disposed that the latch 191 may be engaged by the 90 stud 161 carried by the plate 100, the arrangement of the latch being such as to be deflected by the stud moving toward the machine 25, without actuating the lever 190, but to actuate the lever when the stud engages 95 the latch in moving away from the machine 25. The lever 190 is mounted upon a fulcrum pin 194 which is carried by a block 195 affixed to the controller 150. A pivot pin 196 carried by the lever 190 connects 100 the lever with a link 197, and this link extends to the pin 174 which coöperates with the detent 172. The link 197 and the adjacent arm of the bell-crank 166 coöperate the same as toggle members, with the result that 105 the lever 190 is tilted upon its fulcrum 194 when the lifting device 168 lifts the rod 40. When the lever 190 is in the position shown by Fig. 6, the latch 191 stands in the path of the pin 161, but when the lifting device is 110 lifted so as to place the pin 174 upon the detent 172, the lever 190 tilts so as to carry the latch 191 out of the path of the stud 161. The safety device is thus moved to inoperative 115 position whenever the pin 174 is caught by the detent 172. Supposing, however, the clutch mechanism is reversed while the stud 161 is between the latches 162 and 191. In this event the sliding carriage will be retracted from the machine 25 without 120 disconnecting the rod 40 from the lever 43, and the feed barrel will continue to oscillate while the sliding carriage is approaching the three-armed lever 96. The plate 100 will 125 not actuate the lever 96 under these condi- 130

tions, because the clutch mechanism will be thrown into the "forward" drive position when the stud 161 engages the latch 191. At the time of such engagement the pin 196 at the lower end of the lever 190 will serve as a fulcrum, and the movement imparted to the lever 190 by the stud 161 will shift the controller 150 to "forward" driving position; and although the feed barrel may 10 continue to oscillate, the lever 96 will not be operated to transfer a blank strip from the magazine.

Having thus explained the nature of my said invention and described a way of constructing and using the same, although without attempting to set forth all the forms in which it may be made or all the modes of its use, what I claim is:

1. Strip-handling mechanism comprising 20 means for feeding a blank strip, a magazine for blank strips, sliding members arranged to carry a blank strip from said magazine to said feeding means, and swinging members arranged to coöperate with said sliding members to clamp the blank strip, the axes of said swinging members being transverse to the plane of carrying movement of the strip.

2. Strip-handling mechanism comprising 30 means for feeding a blank strip, a magazine for blank strips, means arranged to carry a blank strip from said magazine to said feeding means, and a pivotally mounted member arranged to overlie the strip on said carrying means and move therewith to said feeding means, the axis of said pivotally mounted member being transverse to the plane of carrying movement of the strip.

3. Strip-handling mechanism comprising 40 means for feeding a blank strip, a magazine for blank strips, sliding means arranged to carry a blank strip in a straight path from said magazine to said feeding means, and a member arranged to swing about an axis toward and from said feeding means to hold the blank strip on said carrying means, said axis being transverse to the plane of carrying movement of the strip.

4. Strip handling mechanism comprising 50 a feed barrel, means movable through said barrel for feeding a strip by engagement with an end of the strip, said barrel having an opening in its side to receive a strip, means for carrying a strip into said barrel 55 through said opening, and means for positioning one end of the strip for engagement by said feeding means, said positioning means being movable by said feeding means from strip-engaging position.

60 5. Strip handling mechanism comprising a feed barrel having an opening in its side for receiving a strip, means movable through said barrel for feeding a strip, means for transferring a strip into said barrel through 65 said opening, and means movable into said

barrel by said transferring means for holding an end of the strip in position to be operatively engaged by said feeding means, said strip-holding means being movable by said feeding means while said transferring means is in operative engagement with said strip. 70

6. Strip handling mechanism comprising bodily movable means for engaging the rear end of a blank strip to feed the strip endwise, means for transferring a blank strip laterally into operative position for feeding by said feeding means, coöperative strip-engaging members for holding the rear end of the strip in position for engagement by 75 said feeding means, and yielding means for moving said strip-engaging members to operative position, said strip-engaging members being displaceable from operative position by said feeding means. 80

7. The combination with instrumentalities for operating upon a blank strip, of means movable toward and from said instrumentalities for feeding a blank strip, a continuously rotating driver, reversing means adapted to be connected with said driver to transmit movement from said driver to said feeding means, a power-driven actuator, and means including a member movable by said feeding means into the path of said actuator 90 for transmitting movement from said actuator to operatively connect said reversing means with said driver. 95

8. The combination with instrumentalities for operating upon a blank strip, of means movable toward and from said instrumentalities for feeding a blank strip, a continuously rotating driver, disconnectible means adapted to be driven by said driver for moving said feeding means, an actuator driven independently of said feeding means, connecting means adapted to be operated by said actuator for operatively connecting said disconnectible means with said driver, and means movable by said feeding means 100 into the path of said actuator for transmitting movement from said actuator to operate said connecting means. 110

9. Strip handling mechanism comprising a feed slide having provisions for engaging a blank strip, means for guiding the strip, disconnectible means for oscillating said guiding means, means operable by said slide for disconnecting said oscillating means, means operable by said slide for transferring a blank strip into said guiding means, and means for preventing action of said slide upon said transferring means while said oscillating means is operatively connected with 115 said guiding means. 120

10. The combination with instrumentalities for operating upon a blank strip; of a strip-engaging member having a passageway for guiding a blank strip to said instrumentalities, coöperative leaf springs for engag- 130

ing opposite sides of the blank strip to guide the forward end of the strip into said passageway, means for guiding the blank strip to said springs, means for turning said guiding means to adjust the blank strip with relation to said instrumentalities, said first-mentioned member and said springs being carried by said guiding means so as to be turned thereby, and means for feeding the 10 blank strip to said instrumentalities.

11. Strip-handling mechanism comprising means for engaging a blank strip to feed the same, a magazine for blank strips, and means for transferring a blank strip from 15 said magazine to said feeding means, said transferring means including strip-holding means for holding one end of the strip in position for said feeding means to operatively engage the strip, said strip-holding means

being arranged to be displaced from the 20 strip by said feeding means.

12. Strip-handling mechanism comprising means for engaging a blank strip to feed the same, a magazine for blank strips, and means for transferring a blank strip from 25 said magazine to said feeding means, said transferring means including strip-clamping means for holding one end of the strip in position for said feeding means to operatively engage the strip, said strip-clamping 30 means being arranged to be displaced from the strip by said feeding means.

In testimony whereof I have affixed my signature, in presence of two witnesses.

HERBERT C. LEONARD.
